UNITED STATES PATENT OFFICE.

GEORGE B. PROCHASKA, OF NEW ORLEANS, LOUISIANA.

SPARK-ARRESTER.

SPECIFICATION forming part of Letters Patent No. 469,271, dated February 23, 1892.

Application filed February 24, 1891. Serial No. 382,513. (No model.)

To all whom it may concern:

Be it known that I, GEORGE BOUTCHER PROCHASKA, a citizen of the United States, residing at New Orleans, in the parish of Orleans and State of Louisiana, have invented certain new and useful Improvements in a Smoke-Consumer and Dust and Soot Collector; and I do declare the following to be a full, clear, and exact description of the invention, such as will enable others skilled in the art to which it appertains to make and use the same.

My invention relates to improvements in devices for depleting smoke of soot and other particles of combustion, whereby it is discharged in a gaseous or vapor state; and it consists in the construction, novel combination, and adaptation of parts hereinafter described, and particularly pointed out in the claim annexed.

In the accompanying drawing the figure is a side elevation of my improved apparatus complete.

Referring by letter to the said drawing, E designates a furnace, and A the smoke-pipe thereof, which may be of any ordinary or approved construction. The said flue A is provided adjacent to its junction to the furnace with a breeching C of the ordinary construction; but this breeching may be dispensed with, if desired, and the main pipe run into the furnace.

Within the drum B, which encircles the pipe A above the breeching C and which is of a diameter greater than the pipe, is arranged a deflector-plate B', through the medium of which a portion of the soot from the arising smoke is detained momentarily in the drum to allow of the condensing of any steam that might be discharged.

The lower portion of the pipe A, as shown in dotted lines at a, extends up into the drum B a sufficient distance to form in conjunction with the wall of the drum a receptacle for the water of condensation, which is drawn off through a depending pipe D, connected with the drum.

At a suitable point in the pipe A above the drum B, I arrange a gate or damper M, which is opened when the furnace-fire is first started to afford a strong draft thereto, but which is closed after the fire is started to send the

smoke through the filtering apparatus, presently to be described.

Leading from the smoke-flue A at a point between the drum B and damper M is a flue G, which is provided at a suitable point in its length with a damper N, which is ordinarily closed when the valve M in the pipe is open, and vice versa. This branch flue G leads to a fan-chamber H, within which a suction or draft fan is rotated by any suitable power, the shaft Q of said fan being provided with a band-pulley, as illustrated.

The fan-wheel within the chamber H may be of any ordinary construction capable of creating a strong draft, whereby the smoke is lead down through the pipe G.

Leading from the fan-chamber H at a suitable point, preferably at the top thereof, as shown, is a flue or pipe K, which leads into the upper side of a boiler or water-receptacle F, which may be of any form and size suitable to the requirements placed upon it. This water-receptacle F is preferably placed in a horizontal position, as shown, whereby the smoke and particles of combustion are given a greater sweep over the water contained therein, which is preferably kept at about the proportional height shown.

Leading from the receptacle F at a distant point from the entrance of the pipe K is a discharge-pipe L, through which the smoke, gas, or vapor which has been depleted of the particles of combustion passes. This flue or pipe L, which is provided with a gate or damper O, discharges into the main flue A above the valve M.

The several dampers or valves in the respective flues are provided with operating-cords P, whereby they may be adjusted conveniently by a person standing upon the ground.

In operation when the valve M is closed, as shown, the smoke passes up and is led through the pipe G, the valve N being open, into the fan-chamber H, thence through the pipe K into the water-receptacle, where it passes over the water, thence in its depleted gaseous state into the pipe L, and finally is discharged into the main pipe A above the valve M therein.

Having described my invention, what I claim is—

The combination, with a furnace, of a smoke-

pipe or uptake in two sections, with a space between them, a drum surrounding the said pipe and connecting the sections thereof, a deflector arranged in said drum, a drain-pipe leading from the bottom of the drum, a damper arranged in the smoke-pipe above the drum, a branch pipe leading from the smoke-pipe or uptake at a point beneath the valve therein, a fan-chamber at the opposite end of said branch pipe, a fan arranged in said chamber, a pipe leading from the fan-chamber and discharging into a water-receptacle,

the said water-receptacle, and a pipe leading therefrom and discharging into the smoke-pipe or uptake above the valve therein, all 15 adapted to operate substantially as and for the purpose set forth.

In testimony whereof I affix my signature in presence of two witnesses.

GEORGE B. PROCHASKA.
